Primary Examiner — Khawaja Anwar*Assistant Examiner* — Mojtaba Tehrani(74) *Attorney, Agent, or Firm* — Fox Rothschild LLP(57) **CLAIM**

The ornamental design for a firearm bolt handle, as shown and described.

DESCRIPTION

FIG. 1 is an isometric view of a firearm bolt handle, showing our new design;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

The dot-dash broken line in the drawings discloses the boundary of the claim, and the evenly broken line in the drawings depicts unclaimed portion of the firearm bolt handle only. The broken lines form no part of the claimed design.
